(57) **CLAIM**

The ornamental design for a reflector for a recessed lighting fixture, as shown and described.

DESCRIPTION

FIG. 1 is a front, left-side, and bottom isometric view of a reflector for a recessed lighting fixture showing the new design.

FIG. 2 is a front elevation view of the reflector for a recessed lighting fixture.

FIG. 3 is a left-side elevation view of the reflector for a recessed lighting fixture.

FIG. 4 is a right-side elevation view of the reflector for a recessed lighting fixture.

FIG. 5 is a rear elevation view of the reflector for a recessed lighting fixture.

FIG. 6 is a bottom plan view of the reflector for a recessed lighting fixture.

FIG. 7 is a top plan view of the reflector for a recessed lighting fixture.

FIG. 8 is a front, left-side, and bottom isometric view of a second embodiment of a reflector for a recessed lighting fixture.

FIG. 9 is a front elevation view of the reflector for a recessed lighting fixture.

FIG. 10 is a left-side elevation view of the reflector for a recessed lighting fixture.

FIG. 11 is a right-side elevation view of the reflector for a recessed lighting fixture.

FIG. 12 is a rear elevation view of the reflector for a recessed lighting fixture.

FIG. 13 is a bottom plan view of the reflector for a recessed lighting fixture; and,

FIG. 14 is a top plan view of the reflector for a recessed lighting fixture.

The broken lines in the drawings represent portions of the reflector for a recessed lighting fixture that form no part of the claimed design.
